UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

AMMUNITION-HOISTING APPARATUS FOR ORDNANCE.

1,402,401.

Specification of Letters Patent.

Patented Jan. 3, 1922.

Application filed September 4, 1920. Serial No. 408,325.

To all whom it may concern:

Be it known that we, Sir ARTHUR TREVOR DAWSON, Bart., and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to Ammunition-Hoisting Apparatus for Ordnance, (for which I have filed application in Great Britain, No. 21,098, filed Aug. 27, 1919.) of which the following is a specification.

This invention relates to ammunition hoisting apparatus for ordnance and is particularly applicable to such apparatus described in the specification of our co-pending application Serial No. 408,323, filed September 4, 1920, in which the magazine is arranged below the level of the shell room and the powder charges are raised in a lifting cage to a position opposite the shell room in which position they are transferred to a second lifting or gun loading cage which also receives a projectile from the shell room.

According to the present invention we provide a trolley or carrier which is mounted on a guide arranged transversely to the ammunition trunk and serves to transport the projectiles from the bogie in the shell room to the gun loading cage. The inner portion of the guide may be hinged and may serve to bridge the compartment of the trunk in which moves the first of the aforesaid lifting cages, this portion being raised so as to clear this lifting cage during its ascent in the said compartment to the position for transferring the powder charges into the upper part of the second lifting or gun loading cage.

On the gun platform we may provide means such as power operated chain rammers for transferring the charges and projectiles from the second lifting or gun loading cage into a flash-proof conveyor arranged at the rear of the gun platform and contiguous to the breech end of the gun, power operated means being provided for traversing the said conveyor behind the gun and guides being provided for causing it to take up a correct position in line with the bore of the gun for fixed angle loading.

In order that the said invention may be

clearly understood and readily carried into effect we will now describe the same more fully with reference to the accompanying drawings, in which:—

Figure 1 is a sectional side elevation showing more or less diagrammatically ammunition hoisting apparatus constructed in accordance with our invention, and

Figure 2 is a sectional rear elevation of the portion of the hoisting apparatus of Figure 1 that serves the left hand gun in a twin gun turret.

Figure 3 is a side elevation on a larger scale showing more clearly the arrangement of the aforesaid guide for the projectile trolley or carrier, and

Figure 4 is a rear elevation on a larger scale showing more clearly the arrangement of the aforesaid conveyor.

A is the turret and A' is the ammunition trunk which moves with the turret in training and A² is the gun loading cage mounted to move vertically in the trunk on guide rails carried thereby. B is the shell room, B' is the usual bogie arranged in the shell room, C is the magazine arranged below the level of the shell room, C' is the lifting cage by which the powder charges are raised to a position opposite the shell room for being transferred to the second lifting or gun loading cage A², this cage being disposed in a compartment B² projecting from the side of the trunk, and C² is the powder charge container which is arranged at the lower part of the compartment B² and serves for the transfer of the powder charges from the magazine C to the cage C'. This container (and also each of the cages A² and C') preferably has a rotary flash-proof receptacle for the powder charges as is described in the specification of our co-pending application Serial No. 408,322, filed September 4, 1920.

D is the aforesaid trolley or carrier mounted to travel between the bogie and the cage A² and D', D' represent transverse guide rails constituting the aforesaid guide for the said trolley or carrier. The inner portions D² of these guide rails are pivoted at d' to the outer portions and serve when in the horizontal position to bridge the compartment B² in which the cage C' is disposed. The said inner portions of the guide rails are moved to the inoperative and opera-

tive positions by a hand lever D^x (see Figure 3). E is the aforesaid movable flash-proof conveyor which is arranged on the gun platform and into which the powder charges and the projectile are transferred 5 from the cage A^2 by means of chain ram-
mers e, e' , a fixed bridge piece E' being pro-
vided between the rear end of the cage and
the front end of the conveyor. The said
10 conveyor is adapted to be traversed by a
press E^2 mounted on the gun platform, from
its receiving position behind the cage A^2 to
its discharging position behind the gun, and
in order that the conveyor may, in moving
15 to its discharging position, assume an in-
clined position in line with the bore of the
gun for loading at a fixed angle, a suitable
arrangement of guides is provided on which
the conveyor moves so that as the latter is
20 being moved to its discharging position it
will become automatically tilted. Two guides
 E^3, E^{3x} (Figure 4) are provided for this
purpose, the former of which is the front
guide, being inclined and the guide E^{3x} ,
25 which is the rear guide being horizontal.
The press E^2 is arranged at an angle which
is half that at which the guide E^3 is in-
clined. The said conveyor is provided with
movable doors, as is well understood, for
30 allowing the powder charges to drop onto
the projectile tray portion of the conveyor
after the projectile has been rammed into
the gun, the charges being deposited in one
complete length so as to be rammed by one
35 stroke of the rammer the casing of which
is indicated at E^4 in Figure 1 and which is
carried by the conveyor.

What we claim and desire to secure by
Letters Patent of the United States is:—

40 1. In ammunition hoisting apparatus for
ordnance, the combination with the ammu-
nition trunk, the shell room and the maga-
zine arranged below the level of the shell
room, of a compartment extending from the
45 side of the trunk, a lifting cage arranged
in said compartment for raising powder
charges to a position opposite the shell room,
a gun loading cage arranged in the trunk,
means for permitting the transfer of the
50 powder charges from said lifting cage to said
gun loading cage when said cages are oppo-

site the shell room, a guide arranged trans-
versely to the trunk and connected thereto
and a carrier mounted on said guide for
transporting shells from the shell room to 55
said gun loading cage.

2. In ammunition hoisting apparatus for
ordnance, the combination with the ammu-
nition trunk, the bogie thereon, the shell room
and the magazine arranged below the level 60
of the shell room, of a compartment extend-
ing from the side of the trunk, a lifting cage
arranged in said compartment for raising
powder charges to a position opposite the
shell room, a gun loading cage arranged in 65
the trunk, means for permitting the transfer
of the powder charges from said lifting
cage to said gun loading cage when said
cages are opposite the shell room, a guide ar-
ranged transversely to the trunk and con- 70
nected thereto and a carrier mounted on
said guide for transporting shells from said
bogie to said gun loading cage.

3. The combination with the elements
claimed in claim 1, of a hinged inner portion 75
of the guide for the shell carrier, said inner
portion when in the horizontal position
serving to bridge the compartment of the
trunk in which the lifting cage is arranged.

4. The combination with the elements 80
claimed in claim 2, of a hinged inner portion
of the guide for the shell carrier, said inner
portion when in the horizontal position serv-
ing to bridge the compartment of the trunk
in which the lifting cage is arranged. 85

5. In ammunition loading apparatus for
ordnance, the combination with the gun
platform and the gun loading cage, of a
conveyor mounted on transverse guides on
said platform, means for ramming the pow- 90
der charges and the shell from said cage to
said container and means for moving said
conveyor on said guides into a loading pos-
ition behind the gun, said transverse guides
being so arranged that during this move- 95
ment said conveyor is automatically tilted
to assume an inclined position correspond-
ing to the loading angle of the gun.

In testimony whereof we affix our signa-
tures.

ARTHUR TREVOR DAWSON,
JAMES HORNE.
